PEBBLE FLOW CONTROL FOR A PEBBLE
HEAT EXCHANGERLouis C. Bearer, Bartlesville, Okla., assignor to
Phillips Petroleum Company, a corporation of
Delaware

Application July 15, 1949, Serial No. 104,964

9 Claims. (Cl. 209—247)

1

This invention relates to a solid material feeder. In one of its more specific aspects, it relates to a pebble feeder in pebble heater apparatus. In another of its more specific aspects, it relates to an improved means and method for controlling the speed and volume of pebble flow through pebble heat exchange apparatus.

Thermal treating and conversion processes which are carried out in so-called pebble heater apparatus utilize a fluent mass of solid heat exchange material, which mass is heated to a high temperature in a first heat exchange chamber and is then caused to contact reactant materials in a second heat exchange chamber furnishing heat to the reactant materials for the thermal treating or conversion thereof. The conventional pebble heater apparatus generally comprises two chambers which may be disposed in substantially vertical alignment. The solid heat exchange material is introduced into the upper portion of the first or upper chamber. That material forms a moving or fluent bed of solid heat exchange material which flows downwardly as a contiguous mass through the chamber in direct heat exchange with a first fluid heat exchange material. The solid heat exchange material is heated to a relatively high temperature in the heat exchange and is then passed to a second chamber in which the hot solid heat exchange material is caused to contact a second gaseous material in a second direct heat exchange relation, furnishing heat for the treatment or conversion of the gaseous material.

Flow of solid heat exchange material through pebble heat exchange apparatus is in many instances quite difficult to control. When the apparatus is utilized for the purpose of converting hydrocarbons, the flow rate of pebbles through the pebble heater apparatus is very critical to the efficient conversion of the hydrocarbons. It is only by the closest control of the pebble flow rate that it is possible to prevent the over-conversion of the gaseous hydrocarbons by reason of excessive temperatures within the conversion chamber or to prevent insufficient conversion of the hydrocarbons by reason of insufficient temperatures within the conversion chamber. The flow rate of solid material has heretofore been partially controlled by the utilization of many types of flow controllers. Conventional star valves, slide valves, rotating tables, screen conveyors, conveyor belts, and the like have been used for the purpose of controlling the flow of solid materials through heat exchangers. Star valves have proved to be rather impractical in

2

pebble heater apparatus for the reason that considerable crushing of pebbles is caused thereby. Insufficient direct control of solid material flow is obtained when using conventional slide or gate valves. The slide or gate valves also tend to cause bridging of pebbles when nearly closed. All of these, but especially the screw conveyor, give prohibitive abrasion losses because of having sliding contact with the extremely hard pebbles. Also, all of these devices have moving parts which are exposed to the atmosphere within the pebble apparatus. The temperature of the pebbles at the feeder may run as high as 1000° to 1200° F. which makes proper lubrication exceedingly difficult, even with water-cooled bearings. Pebble dust from this atmosphere gets into the bearings and causes very excessive wear. Moving parts also make difficult the problem of sealing against gas leaks when super-atmospheric pressures are used, as is becoming more and more common, because some, and usually all, of the moving parts have connections with the outside atmosphere.

Generally speaking, this invention comprises the improvement of pebble heat exchange apparatus by the utilization of an improved vibratory pebble feeder which avoids all of the above difficulties and yet provides for accurate, automatic control of the pebble flow. The feeder is vibrated in such a manner as to make lateral flow of pebbles possible and improvements are provided so as to overcome any inherent fluctuations and inaccuracies.

An object of this invention is to provide an improved method for controlling the flow of solid materials through a solid material system. Another object of the invention is to provide an improved means for controlling the rate of flow of solid materials through a solid material system. Another object of the invention is to provide a means for controlling the rate of flow of pebbles through pebble heat exchange apparatus. Another object of the invention is to provide an improved method for controlling the rate of flow of pebbles through pebble heat exchange apparatus. Other and further objects and advantages will be apparent to those skilled in the art upon study of this disclosure and the accompanying drawings.

Solid heat exchange material which is conventionally used in pebble heat exchange apparatus is generally called "pebbles." The term "pebbles" as used herein denotes any solid refractory material of flowable size and form having the capacity to carry large amounts of heat

from one pebble heat exchange chamber through a gas heating or conversion chamber without rapid deterioration or substantial breakage. Pebbles conventionally used in pebble heater apparatus are substantially spherical and range from about $\frac{1}{8}$ inch to about 1 inch in diameter. In a high temperature process, pebbles having a diameter between $\frac{1}{4}$ inch and $\frac{3}{8}$ inch are preferred. The pebbles must be formed of a refractory material which will withstand temperatures at least as high as the highest temperature attained in the pebble heat exchange chambers. The pebbles must also be capable of withstanding temperature changes within the apparatus. Refractory materials, such as metal alloys, ceramics, or other material having the properties above described may be utilized to form such pebbles. Silicon carbide, alumina, periclase, beryllia, stellite, thoria, zirconia, and mullite may be satisfactorily used to form such pebbles or may be used in admixture with each other or with other materials. Pebbles formed of such materials, particularly of alumina and mullite, when properly fired, serve very well in high temperature operations, some withstanding temperatures up to about 3500° F. Pebbles which are used may be either inert or catalytic when used in any selected process.

Understanding of this invention will be facilitated upon reference to the diagrammatic drawings in which Figure 1 is an elevation of pebble heater apparatus embodying the pebble feeder of this invention. Figure 2 is a top view, partly in section, of the pebble feeder of this invention. Figure 3 is a schematic side view, partly in section, of the pebble feeder of this invention which embodies a modification therein. Figure 4 is a top view, partly in section, of the pebble feeder of this invention with a modified gate. Figure 5 is a side view of a section of a pebble conduit showing a measuring device therein.

In Figure 1 of the drawing, first pebble chamber 11 is provided in its upper end with pebble inlet conduit 12 and effluent outlet conduit 13. A first fluid heat exchange material inlet conduit 14 is provided in the lower portion of the first pebble chamber. Although the drawing shows conduit 14 as communicating with the lower portion of first pebble chamber 11 at a single point, it is within the scope of this disclosure that conduit 14 may communicate with the lower portion of chamber 11 by means of a header encircling the lower portion of chamber 11 and communicating with chamber 11 through a plurality of inlets. Second pebble chamber 15 is provided below chamber 11 and is provided in its upper end portion with effluent outlet conduit 16. Pebble conduit 17 is provided so as to communicate between first pebble chamber 11 and second pebble chamber 15. Pebble conduit 17 extends between the lower portion of chamber 11 and the upper portion of chamber 15. Pebble outlet conduit 18 is provided in the lower portion of second pebble chamber 15. Fluid heat exchange material inlet conduit 19 is provided in the lower portion of second pebble chamber 15. Fluid conduit 19, like fluid conduit 14, may be connected with the chamber with which it communicates by means of a header member and a plurality of inlets from the header into the lower portion of chamber 15. Magnetic vibrator 21 is supported from some base, such as second pebble chamber 15 by means of support member 22. Pebble feeder 23 communicates with pebble outlet 18. Feeder 23 and pebble outlet 18 may be structurally unconnected for op-

eration at atmospheric pressure or they may be non-rigidly connected, for instance by means of bellows 24, for operation at superatmospheric pressures. The outlet end of pebble feeder 23 5 likewise communicates with pebble conduit 25 and may be connected thereto by means of bellows member 26. Pebble conduit 25 communicates with the lower end portion of elevator 27 and pebble conduit 28 extends between the upper portion of elevator 27 and pebble inlet conduit 12 in the upper portion of first pebble chamber 11.

Pebble feeder 23 is provided in its lower side portion with a hopper which forms a pebble fines collection chamber. Outlet conduit 29 is provided in the lower portion of the hopper and provides outlet for pebble fines from the pebble heat exchange system. A gate 31 is provided in pebble feeder 23 and, in one modification as is shown in Figure 2 of the drawing, is hinged at one of its ends by hinge member 32 to a sidewall of the pebble feeder. Link member 33 and connecting rod 34 form the means by which actuating member 35 moves gate 31 into position. Connecting rod 34 is preferably threaded as shown in Figure 2 of the drawing, and actuating member 35 is threaded interiorly so as to cooperate with the threads of connecting rod 34 and move connecting rod 34 in response to controller 36. Actuating member 35 can be rotated by any means, not shown, in response to pebble flow through conduit 25.

In one modification of the invention, automatic control is provided by a source of light 37 in one side of pebble conduit 25 and photoelectric cell 38 in the other side of conduit 25 in the direct rays of a beam thrown by light source 37. Photoelectric cell 38 is operatively connected to controller 36. Controller 36 in turn controls the actuation of member 35 for positioning gate 31. In another modification of the invention, as shown in Figure 3, a pressure sensitive device 39 supports, at least partly, the downstream end of screen member 30 and is sensitive to the weight of pebbles flowing across the upper surface of screen member 30. Variations in the weight of pebbles on screen 30 are sensed by device 39 and transmitted electrically, hydraulically, or mechanically to controller 36 for the positioning of gate 31. In yet another though less desirable modification of the invention, as schematically shown in Figure 5 of the drawings, a continuous belt 41 is mounted on pulley members 42 and 43 in the lower portion of pebble conduit 25 and extends to a point adjacent elevator 27. Scale 44 is provided adjacent the upper belt section and is actuated by the weight of pebbles upon the upper surface of the belt. Scale 44 also is operatively connected to controller 36.

Rod 45 of vibrator 21, as is shown in Figure 3 of the drawing extends upwardly and generally in a direction toward the downstream end of pebble feeder 23 and is rigidly affixed to pebble feeder 23 so as to permit spring-loaded connection, by means of a spring, such as for example coil spring 47, of vibrator 21 to feeder 23. Vibrator 21 and spring 47 cooperate by means of opposite forces so that a substantially elliptical path, in a vertical plane parallel to the feeder, is described by feeder 23. It is this elliptical motion of feeder 23 which causes the pebbles to progress across screen 30. Pebble feeder 23 is laterally disposed in relation to the downflow of pebbles from second pebble chamber 15. The outlet end of the feeder is positioned at an angle not greater than the angle of repose of the flowing material below

the inlet end thereof so that the pebbles employed will not substantially continue entering the feeder and flow therethrough after the vibrator has been halted. The angle of repose of pebbles is generally in the neighborhood of 30° from the horizontal. More positive control of pebble flow is obtained when the angle at which the pebble feeder is disposed is considerably less than the angle of repose.

In the operation of the device shown as Figure of the drawings, pebbles are passed into the upper portion of chamber 11 through pebble inlet conduit 12 and flow downwardly therethrough as a fluent, gas-pervious, contiguous mass. A first fluid heat exchange material is passed into the lower portion of chamber 11 and upwardly through the fluent mass of pebbles. Gaseous effluent material is removed from the upper portion of chamber 11 through effluent outlet conduit 13. When the pebble heat exchange apparatus is a pebble heater apparatus, the fluid heat exchange material which is supplied to the lower portion of first pebble chamber 11 is a hot heat exchange gas or a fuel which is burned on the surface of the downflowing pebbles, imparting heat thereto. The hot gas may be a hot combustion gas formed by the combustion of fuel outside of chamber 11. At times it is desirable to utilize a combustion chamber in the lower portion of the pebble heater chamber and a separate combustion chamber is formed below the pebble mass in chamber 11. Hot combustion gases formed by the combustion of fuel within such a combustion chamber are passed into the lower portion of the pebble bed through perforations in a separation member in the lower portion of the chamber.

Pebbles from chamber 11 are passed into the upper portion of second pebble chamber 15 through pebble conduit 17. The pebbles form a fluent, gas-pervious, contiguous mass within chamber 15 and flow downwardly therethrough. A second fluid heat exchange material is passed into the lower portion of chamber 15 through fluid heat exchange material inlet conduit 19. The pebbles in chamber 15 act in the heat exchange with the fluid heat exchange material in a manner contra to that in which it acted in the heat exchange in chamber 11, i. e., if the pebbles take up heat in the first heat exchange in chamber 11 they give up heat in the heat exchange in chamber 15. When the pebbles are heated in chamber 11, the pebbles carry heat into chamber 15 for the purpose of providing heat of conversion to materials which are supplied to chamber 15 through conduit 19.

Pebbles from chamber 15 gravitate through pebble outlet conduit 18 into the inlet end of pebble feeder 23. Pebbles which are passed into a chamber or open space through an inlet in its upper end tend to flow downwardly and outwardly from the inlet and form a cone of pebbles. After the pebbles have formed this cone, the slope of which is the angle of repose of the pebbles, it apparently is impossible to cause them to move any further laterally merely by applying pressure to the pebbles from above. The same is true for the pebbles entering pebble feeder 23 so that no pebble flow across screen 30 is possible when feeder 23 is still. In this invention, vibratory motion is supplied to pebble feeder 23 by means of vibrator 21. Pebble feeder 23 is vibrated so that the pebbles are caused to move laterally along the surface of screen 30. Positive movement of the pebbles and some control of

their flow is therefore obtained by controlling the amplitude of vibration of the pebble feeder. However, it has been found that exact control of pebble flow therethrough, especially in the case of large-capacity feeders, can be obtained only through the help of this invention which modifies the passageway through the pebble feeder by means of gate 31. Gate 31 is moved in response to controller 36 by actuating means 35. Controller 36 acts in response to impulses received from a pebble flow measuring device such as one of the three measuring devices described above.

The combination of the photoelectric cell and the light source is utilized in the preferred modification of this invention. Use of this type of measuring device is preferred because it eliminates all moving parts which would be contained in the hot, dust-laden atmosphere of the pebble apparatus. At slow rates of flow through pebble feeder 23 the individual pebbles can be counted by a counter connected with the photoelectric cell. At faster rates of flow, however, the flow rate is measured in terms of the intensity of light passing through the stream of pebbles and striking the photoelectric cell. Impulses from photoelectric cell 38 are supplied to controller 36 which actuates a motor, not shown, which operates member 35 and baffle 31 so as to maintain a predetermined flow of pebbles through pebble conduit 25.

In a second modification of the invention, the weight of pebbles flowing across the screen member in the floor of pebble feeder 23 makes an impression upon the pressure- or weight-sensitive member 39 so as to supply an impulse to controller member 36 which causes baffle 31 to be positioned. A curved weir may be used at the downstream end of screen 30 so that the depth of pebbles, and therefore their weight, on the screen will vary directly with the rate of flow.

In the third modification of the invention, a continuous belt is rotated in the lower portion of pebble conduit 25 so as to catch pebbles from the outlet of pebble feeder 23 and to convey them to the lower portion of elevator 27. The weight of the pebbles carried on belt 41 is measured by scale 44 which actuates controller 36 to position baffle member 31 in response thereto.

Each of the above modifications makes possible very close control of the flow of pebbles through a pebble heat exchanger. By this new method of control, variation in pebble flow are automatically and continuously smoothed out. Variations in flow commonly occur from temporary bridging of pebbles in the pebble outlet 18, from oversensitivity of the feeder device, and from ordinary fluctuations in the amount of power supplied to the feeder by the prime mover employed. Pebble feeder 23 also acts to separate pebble fines, which result from breakage and attrition within the pebble heat exchanger system, from pebbles of desired size. The pebble fines are separated by screen member 30 and are removed from the lower portion of pebble feeder 23 through fines outlet 29.

Although screen member 30 is shown in Figure 3 of the drawing as a regular interwoven screen, that portrayal is entirely schematic. A grizzly or other type of screen may be used, depending chiefly on which type is most practical for the size of pebbles employed. Vibrator 21 could be positioned within pebble feeder 23 so as to vibrate only screen member 30, if desired. However, it is advantageous to maintain the vibrator outside of feeder 23, as shown, so that

the vibrator is not subjected to the hot, dust-laden atmosphere. It is also possible, by keeping the vibrator outside, to rigidly affix screen member 30 in the lower portion of the pebble feeder and thus eliminate all moving parts within the dust-laden atmosphere. In addition the construction of the feeder housing is kept smaller and simpler with the vibrator outside.

Although gate member 31 has been described only as a hinged member, it may be a slide-type gate, as shown in Figure 4 of the drawings. In Figure 4 member 31 is shown to be actuated directly by a diaphragm motor instead of a threaded member 35, as shown in Figure 2. It is evident that a pneumatic piston, a hydraulic piston, or other suitable follower device may be substituted for the diaphragm motor. Controller 36 may be arranged to supply the air, hydraulic fluid, electrical current, or other power-supplying medium directly to the motor chosen to operate gate 31 and in the quantities which should secure the desired positioning of the gate. On the other hand, a positioner may be connected to gate 31 or rod 34 to receive the impulse from controller 36. This positioner checks on the actual position of the gate and permits force to be applied until the gate 31 is at the position called for by controller 36. The details and choice of the controller and follower mechanisms are not part of this invention but these are mentioned to indicate how adaptable this invention is to means already known to the art.

Although gate 31 has been shown as extending across feeder 23 from the side, it is within the scope of this disclosure that gate 31 may extend upwardly through the bottom of the feeder or be pivotally affixed intermediate its ends to the walls of the feeder. Partial control of solid material flow may also be obtained by varying the elevation of one end of the pebble feeder in response to solid material flow therethrough.

As will be evident to those skilled in the art, various modifications of this invention can be made or followed in the light of the foregoing disclosure and discussion without departing from the spirit or scope of the disclosure or of the invention.

I claim:

1. A pebble feeder comprising a laterally disposed pebble conduit member having an inlet in one end and an outlet in its other end, said outlet being no lower than 30° downwardly from said inlet; an adjustable baffle member intermediate the ends of said conduit and disposed within and supported by the walls of said conduit, said baffle being adapted to variably modify a pebble passageway through said conduit; means to adjust said baffle; and a vibrator extending upwardly and generally toward the downstream end of said conduit operatively connected to the upstream end portion of said conduit, said vibrator being adapted to supply elliptical motion to said conduit so as to move pebbles through said conduit.

2. The pebble heat exchanger of claim 7, wherein said adjustable baffle is pivoted to a wall of said pebble conduit; an actuating member extending outside of said pebble conduit and operatively attached to said baffle member; and said controller operatively connecting said actuating member and said measuring device.

3. The pebble heat exchanger of claim 7, wherein said measuring device comprises a photoelectric counter in one side of said outlet pebble conduit and a cooperating light source in the

5 side of said outlet conduit opposite said photoelectric counter, said light source being disposed so that light therefrom is spotted on said photoelectric counter across the passage formed by the walls of said outlet pebble conduit.

4. The pebble heat exchanger of claim 6, wherein a screen is positioned in the bottom side portion of said pebble conduit forming a floor therein; and a fines collection chamber below said screen and having an outlet in its lower portion.

5. The pebble heat exchanger of claim 6, wherein said vibrator is an electromagnetic type vibrator.

6. A pebble feeder comprising a laterally and downwardly disposed pebble conduit having an inlet conduit in its upper end and an outlet conduit in its lower end, said outlet being disposed no lower than 30° from said inlet; an adjustable baffle member within and supported by said conduit and adapted to variably modify a pebble passageway through said feeder; a vibrator operatively connected to said pebble feeder so as to supply elliptical motion thereto; and a controller operatively connected to and adapted to variably move said adjustable baffle member.

7. A pebble feeder comprising a laterally and downwardly disposed pebble conduit having an inlet conduit in its upper end and an outlet conduit in its lower end, said outlet being disposed no lower than 30° from said inlet; an adjustable baffle member within said conduit and adaptable to variably modify the opening through a pebble passageway through said feeder; a vibrator extending upwardly and generally toward the downstream end of said conduit operatively connected to the upstream end portion of said pebble feeder; a controller operatively connected to and adapted to variably move said adjustable baffle member; and solids flow measuring means operatively connected to said outlet conduit and said controller.

8. A pebble feeder comprising a laterally and downwardly disposed pebble conduit having an inlet conduit in its upper end and an outlet conduit in its lower end, said outlet being disposed no lower than 30° from said inlet; an adjustable baffle member within and supported by said conduit and adapted to variably modify a pebble passageway through said feeder; a vibrator extending upwardly and generally toward the downstream end of said conduit operatively connected to said pebble feeder; a controller operatively connected to and adapted to variably move said adjustable baffle member; a screen positioned in the bottom side of said laterally and downwardly disposed conduit, forming a floor therein upstream and downstream of said baffle; a fines collection chamber below said screen and having an outlet in its lower portion; and a solids flow measuring means comprising a weight sensitive means operatively communicating between said screen and said controller.

9. The pebble feeder of claim 6, wherein a rotatable, laterally extending continuous belt is provided in the lower portion of said outlet conduit; and solids flow measuring means comprising a scale operatively communicating between the top length of said belt and said controller.
